2213 16th Place, both of Yuma, Ariz.

Filed Mar. 9, 1962, Ser. No. 69,164

Term of patent 7 years

(Cl. D35—1)

FIGURE 1 is a perspective view of a seedling protector, showing our new design; the broken lines on the top indicate that the small rectangular panel is knock-out; FIGURE 2 is an end elevational view thereof; FIGURE 3 is a side elevational view thereof; FIGURE 4 is a top plan view thereof; FIGURE 5 is a bottom plan view thereof; and FIGURE 6 is an enlarged cross-sectional view thereof taken on the line 6—6 of FIGURE 3.

We claim:

The ornamental design for a seedling protector, as shown and described.
